UNITED STATES PATENT OFFICE.

LEO ANDREW SNYDER, OF HAILEYVILLE, OKLAHOMA, ASSIGNOR OF ONE-HALF TO
EDGAR M. JONES, OF HAILEYVILLE, OKLAHOMA.

IGNITION SYSTEM.

1,208,034.

Specification of Letters Patent. Patented Dec. 12, 1916.

Application filed May 8, 1915. Serial No. 26,725.

To all whom it may concern:

Be it known that I, LEO A. SNYDER, a citizen of the United States, and a resident of Haileyville, in the county of Pittsburg 5 and State of Oklahoma, have invented a new and useful Improvement in Ignition Systems, of which the following is a specification.

My invention is an improvement in ignition systems, and the invention has for its 10 object to provide a mechanism of the character specified, adapted for use in gas, gasoline, kerosene or other liquid fuel heating or lighting apparatus, wherein a sparking 15 mechanism is arranged in position to ignite the fuel, the said mechanism being combined with a high tension spark coil, a combined selector switch and timer and a suitable generating apparatus.

20 In the drawings:—Figure 1 is a transverse vertical section of a heater provided with the improvement, Fig. 2 is a partial front view of Fig. 1 with parts in section, and Fig. 3 is an enlarged vertical section of 25 the switch.

The present embodiment of the invention is shown in connection with a heater of usual or desired form, the said heater comprising a casing 1, in which is arranged burners 2, 30 3 and 3^a, the casing being divided into compartments as shown, the said compartments being three in number and designated at A, B and C. The burner 2 is arranged in the compartment A which is the lowest compartment, while the burners 3 and 3^a are arranged in the compartment C.

A spark plug 4 is arranged adjacent to the burner 2, and spark plugs 5 are arranged adjacent to the burners 3 and 3^a. The spark 40 plug 4 is supported in horizontal position by a bracket 6, while the plugs 5 are supported in vertical position by brackets 7, the brackets 6 and 7 being connected to the burner.

A box or casing 8 is arranged outside of 45 the casing 1 near the top thereof, and the said box or casing is designed to support a series of batteries 9, for generating an electric current. A coil 10 of the vibrator type, a high tension jump spark coil of the class 50 commonly used in gas engine ignition work, is arranged above the battery box or casing, the said coil being supported at its ends by brackets 11, connected with the casing 1 of the heater, and a combination selective dis-

tributer and timer 12 is connected to the 55 outer face of the wall of the heater casing adjacent to the coil and above the same.

Leads 13 and 14 lead from the spark plugs 4 and 5, respectively, to the switch 12, the said leads being connected to suitable binding posts 15 and 16 on the switch. A lead wire 17 connects the arm 18 of the switch with one of the terminals 19 of the coil and another lead 17^a connects the other terminal 19^a of the coil with one of the terminals of 60 the battery 9. A lead wire 20 connects the other terminal of the battery with the binding post 31 in a switch casing 12, which is secured to the casing 1 at any desired point, and the binding post extends through the 65 front wall of the casing, being insulated therefrom as shown in Fig. 3. The leads 13 and 14 extend into the casing, and are connected with the buttons or binding posts 15 and 16 inside the casing, and the said posts 70 or buttons are insulated from the casing in the same manner as the post 21, by means of sleeves of insulating material.

The wire 17 which connects one of the terminals of the coil with the switch arm is 75 also connected to a binding post 23 inside the casing, the said post extending through the front wall of the casing to a connection with the switch arm, and the post is insulated from the casing by an insulating 80 sleeve in the same manner as the posts 15—16 and 21.

A contact member or strip 24 is connected to the binding post 21 inside the casing, and a resilient contact member or strip 25 is connected with the binding post 23 in the casing. 85 The free ends of the contact members 24 and 25 are arranged to be contacted when the free end of the strip 25 is pressed rearwardly by means of a push button 26, arranged within an opening in the front wall of the casing. Normally the resiliency of the member 25 holds the members 24 and 25 out of contact with each other. A lead wire 90 22 connects the coil to ground, the ground connection in the present instance being through the metallic casing 1 of the heater.

The leads 13 and 14 are high tension leads for conveying the current to the spark plugs and by means of the switch arm 18, and the 95 push button 26 any of the three plugs may be connected with the coil and battery. When the switch arm is in the position of

Fig. 1 the device is inoperative. If for instance it is desired to ignite the heater 2 the switch arm 18 is shifted on to the button 16. The current now passes from battery through the switch coil to the lead wire 17, and by way of the contact members 24-25 and the lead 20 to battery, and a spark is generated by the spark plug 4 at the burner 2.

10 When it is desired to connect the spark plug 5 of the burner 3 with the coil, the switch arm is shifted to connect the button 15 at the left of the switch casing 12 to the circuit. When the arm is on the button and the button 26 is depressed the spark plug 5 generates the spark at the burner 3. To connect the burner 3^a with the current it is only necessary to place the switch arm 18 on the button 15 at the right of Fig. 2, and 20 then depress the button 26.

It will be evident that with the improved system the burners wherever arranged may be ignited without the necessity of using matches or the like. Furthermore there is no necessity for heating tubes and the danger from explosion and fire is reduced to a minimum. Neither is it necessary to stoop or bend over to light burners arranged in low positions, and the lighting may be done 30 from a distance if desired. The arrangement shown in Fig. 1 is diagrammatic and it is obvious that the burners may be arranged in any desired position.

The burners 2-3 and 3^a are of ordinary 35 type, and the spark plugs are arranged with their terminals in position to have the spark in the line of the discharge from the burners.

It will be evident that whenever the switch arm is in contact with any button 15 or 16, the plug may be caused to spark by depressing the push button 26, and so long as this button is not depressed, no spark will be generated. Hence it will be readily understood that the current cannot be left turned 45 on through negligence thereby exhausting the battery. Whenever the hand is removed from the push button the circuit is broken, regardless of the position of the switch arm. The switch arm is the selector element of the switch, and the push button is the timer element. It will be evident that a series of sparks might be created at

either burner by depressing the push button successively.

I claim:

1. A device of the character specified, for selecting and distributing electric current to a series of spark plugs, and comprising a plate having a series of contact plates or buttons at one end, and adapted for connection with the several plugs, a switch arm pivoted to the plate and adapted to contact with the respective buttons, and adapted for connection with one of the terminals of an electrical circuit, a contact member for connection with the other terminal, a resilient contact arm connected with the switch arm and normally out of contact with the last-named contact member, and having a push button for permitting the said arm to be moved into contact with the said contact member. 55 60 65

2. A device of the character specified, for selecting and distributing electric current to a series of spark plugs, and comprising a plate having a series of contact plates or buttons at one end, and adapted for connection with the several plugs, a switch arm pivoted to the plate and adapted to contact with the respective buttons, and adapted for connection with one of the terminals of an electrical circuit, a contact member for connection with the other terminal, a resilient contact arm connected with the switch arm and normally out of contact with the last-named contact member, and having a push button for permitting the said arm to be moved into contact with the said contact member to close the circuit. 75 80 85

3. In combination with a series of spark plugs, a high tension jump spark coil, a source of electrical energy, and an open circuit in which the coil and the source are interposed, of a support, a series of binding posts on the support, each post being connected to a plug, a switch arm pivoted to the support and adapted to contact with the respective posts, and connected to one of the terminals of the source, a resilient contact arm connected with the switch arm and normally out of contact with the other terminal of the circuit and adapted to be moved toward the said terminal to complete the circuit. 90 95 100

LEO ANDREW SNYDER.
